UNITED STATES PATENT OFFICE.

FREDRICK KIRCHNER, OF BROOKLYN, NEW YORK.

DESIGN FOR A PLUMBER'S TRAP.

SPECIFICATION forming part of Design No. 27,866, dated November 16, 1897.

Application filed September 24, 1897. Serial No. 652,936. Term of patent 14 years.

To all whom it may concern:

Be it known that I, FREDRICK KIRCHNER, a citizen of the United States, residing at Brooklyn, in the county of Kings and State of New York, have invented and produced a new and original Design for a Plumber's Trap, of which the following is a full, clear, and exact description, reference being had to the accompanying drawing, forming a part hereof, in which is represented a side elevation of a trap embodying the features of my design.

The leading features of the design consist in the shape of the body A, which is longitudinally tapering, being widest at the top and

finished off at the bottom with the usual cap A'. An upwardly-extending flange B connects with the side of the body near its lower or contracted end, while at the opposite side of the body a second downwardly-extending flange C joins the body at its wide upper portion.

I claim—

The design for a plumber's trap herein shown and described.

FREDRICK KIRCHNER.
